FIG.3

Des. 208,916

PAGE 4

FIG. 4

FIG. 5

FIGURE 1 is a front perspective view of a central control unit for a data processor embodying my new design;
FIGURE 2 is a left side elevational view thereof;
FIGURE 3 is a right side elevational view thereof;
FIGURE 4 is a rear elevational view thereof; and
FIGURE 5 is a top plan view thereof.

I claim:

The ornamental design for a central control unit for a data processor, substantially as shown.
